US00D976139S

(12) **United States Design Patent** (10) **Patent No.:** **US D976,139 S**
(45) **Date of Patent:** ** *Jan. 24, 2023

(54) **AIRCRAFT TEMPERATURE PROBE**

(71) Applicant: **ROSEMOUNT AEROSPACE INC.**,
Burnsville, MN (US)

(72) Inventors: **Scott D. Isebrand**, Minneapolis, MN
(US); **Andrew Gilb**, Savage, MN (US)

(73) Assignee: **ROSEMOUNT AEROSPACE, INC.**,
Burnsville, MN (US)

(*) Notice: This patent is subject to a terminal disclaimer.

(**) Term: **15 Years**

(21) Appl. No.: **29/758,918**

(22) Filed: **Nov. 19, 2020**

(57) **CLAIM**

The ornamental design for an aircraft temperature probe, as shown and described.

DESCRIPTION

FIG. 1 is a perspective view of an aircraft temperature probe in accordance with an embodiment, showing my new design;

FIG. 2 is a front elevation view of the embodiment shown in FIG. 1;

FIG. 3 is a rear elevation view of the embodiment shown in FIG. 1;

FIG. 4 is a left-side elevation view of the embodiment shown in FIG. 1;

FIG. 5 is a right-side elevation view of the embodiment shown in FIG. 1;

FIG. 6 is a top-down plan view of the embodiment shown in FIG. 1;

FIG. 7 is bottom-up plan view of the embodiment shown in FIG. 1; and,

FIG. 8 is a bottom-up rear perspective view of the embodiment shown in FIG. 1.

The broken lines shown are included for the purpose of illustrating portions of the aircraft temperature probe that form no part of the claim.

1 Claim, 5 Drawing Sheets
